UNITED STATES PATENT OFFICE.

MORGAN DAVIES, OF DENVER, COLORADO.

DESIGN FOR A SHADE-BRACKET.

46,494.

Specification for Design.

Patented Oct. 6, 1914.

Application filed July 25, 1914. Serial No. 853,178. Term of patent 14 years.

To all whom it may concern:

Be it known that I, MORGAN DAVIES, a citizen of the United States, residing at Denver, county of Denver, and State of Colorado, have invented a new, original, and ornamental Design for Shade-Brackets, of which the following is a specification, reference being had to the accompanying drawing, forming part thereof.

The figure is a perspective view of a shade bracket showing my new design.

I claim:

The ornamental design for a shade bracket, as shown.

MORGAN DAVIES.

Witnesses:

ELLEN C. WITTER,
JOSEPHINE J. MINER.
